Primary Examiner — Melanie H Tung*Assistant Examiner* — Darmawan Truong(74) *Attorney, Agent, or Firm* — Studebaker & Brackett PC(57) **CLAIM**

The ornamental design for a display screen or portion thereof with graphical user interface, as shown and described.

DESCRIPTION

FIG. 1. is a front view of a display screen or portion thereof with graphical user interface showing our new design; and, FIG. 2. is an enlarged view of a part 2 shown in FIG. 1. The broken lines showing the display screen or portion thereof form no part of the claimed design. The remaining broken lines showing portions of the graphical user interface form no part of the claimed design. The dot-dash broken lines illustrate boundaries of the claimed design, and form no part of the claimed design.

1 Claim, 2 Drawing Sheets(56)
